CLAIM

The ornamental design for a support for protecting
tubing-mounted cables at the tube coupling, as shown
and described.

DESCRIPTION

FIG. 1 is an isometric view of a cable collar protector
according to the invention;

FIG. 2 is a front view thereof, the rear view thereof
being identical;

FIG. 3 is a right side view thereof the left side view
being identical;

FIG. 4 is a top view thereof;

FIG. 5 is a bottom view thereof; and,

FIG. 6 is an enlarged cross-sectional view taken at 6—6
of FIG. 3 to clarify the front view of FIG. 2.

Fig. 1.

Fig. 2.
